UNITED STATES PATENT OFFICE

2,681,079

RETURN MOVEMENT DEVICE FOR WEAVING
LOOM HEDDLE FRAMESJaime Picanol, Zandberg, Zillebeke-lez-Ypres,
Belgium

Application September 27, 1951, Serial No. 248,612

1 Claim. (Cl. 139—89)

1

The present invention relates to a return device for the drive of the heddle-frames in weaving looms in which the heddle-frames, animated by a vertical alternative movement, are positively displaced in one direction by a driving mechanism and are urged back in the reverse direction by an elastic device. Different systems with spring action have been used as elastic devices, these were placed at the top or at the bottom of the loom, according to the nature and the position of the driving mechanism.

The invention relates to a device of the type using spiral springs which urge the heddle-frames upwardly from their lower to their upper position.

The device, according to the invention, is characterised by the fact that each heddle-frame is placed between a single driving lever situated underneath said heddle-frame to actuate the latter downwardly and a return movement device which has two independent supports fixed above each of the lateral frames of the loom and mounting a spiral spring and a guiding pulley respectively, for each heddle-frame. The inner end of said spiral spring is fixed with relation to its support and the external part of said spring is provided with a pair of flexible belts urging the heddle-frame upwardly. One of said belts is hooked directly to one of the upper corners of the heddle-frame, and the other belt is trained over said guiding pulley to be hooked over to the other upper corner of the heddle-frame.

The return springs for the even numbered heddle-frames are situated at one side of the loom and the return-springs for the uneven numbered heddle-frames are situated at the other side of the loom. On the other hand, the guiding pulleys for the uneven numbered heddle-frames are situated on the first mentioned side of the loom and the guiding pulleys for the even numbered heddle-frames are disposed on the last mentioned side of the loom. Each heddle-frame is urged upwardly by one single spiral spring and downwardly by one single driving lever.

In this manner, the frame of the loom may be substantially modified as compared to the conventional embodiments and the "archivol" or upper cross-beam, which normally extends above the loom and is particularly cumbersome, is no longer necessary. Thus, with the use of the device, according to the present invention, the upper part of the loom becomes substantially free of obstructions and this highly increases the

2

visibility in the weaving rooms allowing better supervision and better illumination of the loom.

A preferred embodiment according to the invention is described, as an example, hereafter with reference to the accompanying drawings, in which:

Figure 1 is a schematic view of the device according to the present invention;

Figure 2 is an elevation view of the essential elements of this device.

Figure 3 is a plan view of the device shown in Figure 2; and

Figure 4 is a general perspective view of a weaving loom provided with the device according to the present invention.

The device, according to the invention, comprises essentially a heddle-frame 1 of conventional type interposed between a single operating lever 2 for positively displacing said heddle-frame downwardly through the intermediary of its lower cross-bar 3 which is hooked to the heddle-frame by the hooks 4, 5 and at least one spiral spring 6 housed in drum 7; one of the ends of said spiral spring is directly or indirectly extended by flexible links consisting of tapes or belts 8, 9. The belt 8 is directly fixed to the adjacent upper corner of the heddle-frame 1 and the belt 9 is trained over an intermediary pulley 10' and is fixed to the other upper corner of said heddle-frame 1.

In the embodiment of Figures 2 and 3, we find these various elements; the drums 7 and 7' house the spiral springs 6 and 6' respectively and the intermediary pulleys 10 and 10' are mounted at the extremity of brackets 11 and 11' respectively thereby forming an arrangement which permits the complete clearing of the upper medium part of the loom. In this case, the drum 7 is rotatably mounted on the upper extremity of a bracket 11 resting directly, through its base 12, on the frame 13 of the loom. This bracket extends in a manner to correctly position the drum 7 so that the latter lies practically in the plane of the associated heddle-frame. The belt 8 is secured to the drum 7 at one end and is directly hooked to the upper edge of the heddle-frame 1 at the other end so as to remain substantially vertical during the different up-and-down movements of the heddle-frame. The intermediary pulley 10' is rotatably mounted at one end of an arm 14' depending from the bracket 11' and is adapted to support the belt 9, so that the portion of the latter comprised between said pulley and the heddle-frame 1 will also remain substantially vertical during the up-and-down movements of

the heddle-frame. The bracket 11 with its depending arm 14 is placed on one side of the heddle-frames while the bracket 11' with its depending arm 14' is placed on the other side of the heddle-frames, so that all the spiral springs 6 of the even numbered heddle-frames such as the heddle-frame 1 and the intermediary pulleys 10 of the uneven numbered heddle-frames such as the heddle-frame 1' are disposed on one side of the loom while the springs 6' of the uneven numbered heddle-frames 1' together with the pulleys 10' of the even numbered heddle-frames 1 are disposed on the other side of the loom. In this manner a perfectly balanced distribution of the elements of the device is obtained and the occupied space is reduced to a minimum. All the spiral springs and the drums of the even numbered heddle-frames are mounted on the same bracket, whereas all the spiral springs and the drums of the uneven numbered heddle-frames are mounted on the opposite bracket. The intermediate pulleys 10' of the even numbered heddle-frames are disposed on a common shaft mounted on an arm 14' and similarly, all the intermediate pulleys 10 of the uneven numbered heddle-frames are disposed on another shaft mounted on the opposite arm 14. In other words, one heddle-frame 1 of each pair of heddle-frames 1 and 1' is connected to a drum 7 disposed on one side of the loom while the other heddle-frame 1' of each pair of heddle-frames 1 and 1' is connected to a drum 7' mounted on the other side of the loom. Due to the fact that the plurality of drums 7 mounted on a common shaft are connected to every second heddle-frame, the successive heddle-frames may be disposed very close to each other and thus no room is wasted. The same holds true for the drums 7' on the other side of the loom and for the pulleys 10 and 10'.

By means of this arrangement, each heddle-frame is positively driven downwardly by a single operating lever disposed at the lower part of the loom, and is pulled back upwardly by the two belts by which it is suspended, these belts being urged by the same spiral spring. The upper

medium part of the loom remains practically free of obstruction allowing a better illumination of the loom and a better visibility of the rear part of the same.

5 It will be possible to make various modifications to the device of the present invention depending more particularly on the means used for the positive drive by a single lever without departing from the spirit and scope of the appended claim.

I claim:

In a return movement device for a plurality of pairs of heddle-frames in a weaving loom, a pair of support brackets mounted on said loom and each extending above one end of said pairs of heddle-frames, a first series of drums rotatably mounted at the upper end of one of said brackets and in vertical alignment with one heddle-frame of said pairs of heddle-frames respectively, a second series of drums mounted on the upper end of the other of said brackets and respectively in vertical alignment with the other heddle-frame of said pairs of heddle-frames, a spiral spring housed within each drum and urging the 10 said drum to rotate, a pair of flexible links for each drum trained over the same and attached at one end to said drum, an arm depending from each of said brackets, a plurality of pulleys rotatably mounted on each of said arms, said 15 pulleys being respectively in alignment with the drums mounted on the opposite brackets, one link of each pair of links being connected to one upper corner of the aligned heddle-frame and the other link of each of said pair of links being 20 trained over an aligned pulley and attached to the other corner of said aligned heddle-frame.
